UNITED STATES PATENT OFFICE.

WILLIAM F. DAVIS, OF WATERLOO, IOWA, ASSIGNOR TO THE DAVIS
GASOLINE ENGINE WORKS COMPANY, OF SAME PLACE.

GRINDING-MILL.

SPECIFICATION forming part of Letters Patent No. 622,914, dated April 11, 1899.

Application filed May 6, 1898. Serial No. 679,881. (No model.)

To all whom it may concern:

Be it known that I, WILLIAM F. DAVIS, a resident of Waterloo, in the county of Black Hawk, State of Iowa, have invented certain new and useful Improvements in Grinding-Mills, of which I do declare the following to be a full, clear, and exact description, sufficient to enable others skilled in the art to make and use the same.

10 The present invention has relation to that class of grinding-mills commonly known as "feed-mills," such mills being more especially adapted for the grinding of corn or other grain to be used as food for stock, and particularly does the invention relate to the class 15 of feed-mills known as "duplex" mills.

In the construction of the class of duplex mills to which my invention more particularly relates it has been heretofore the practice to 20 provide a stationary inner shell or cone, and over this stationary cone was mounted a revolute cone or shell provided at its base with an inner grinding-ring that coöperated with an outer grinding-ring upon the stationary 25 cone and provided upon its outer surface with an outer grinding-ring that coöperated with a grinding-ring held by bolts outside the revolute cone. An example of this type of duplex mill is illustrated in Letters Patent No. 30 604,853, granted for an invention of Thomas Cascaden, Jr., May 31, 1898.

In order to regulate the grinding action of the grinding-rings in the duplex mills of prior construction—such, for example, as the mill 35 set forth in the above-mentioned Cascaden patent—it has been the practice to pass bolts through lugs at the base of the inner stationary cone or shell and up through similar lugs formed upon the outer ring that carried the 40 outermost grinder, the inner shell being also connected by a tripod with a temper-screw or adjusting-screw that passed up through the center-post of the mill. The screw-bolts connecting the lugs of the inner stationary cone 45 or shell with the lugs upon the outer grinding-ring were relied upon not merely to sustain the outer ring, but also to effect its adjustment, the adjustment of the inner shell or grinder being secured by means of the temper-screw. While this prior construction 50 possesses many advantages over other forms

of mills, in practice it is found difficult to so sustain the grinding-rings in position as to secure uniformity of adjustment and uniformity in the grinding action. In the construction of this class of mills, the grinders being formed as plain cheap castings, it follows that the grinding-rings are frequently not truly concentric, and in some instances the eccentricity of the rings amounts to one-half or three-quarters of an inch. Hence it is that although the adjusting-bolts may be accurately set, still the eccentricity of the rings results in an uneven grinding, since the bolts do not permit of an automatic shifting 65 or adjustment of the rings to compensate for their eccentricities. Moreover, with prior constructions of duplex mills the necessity of separate adjustment for the inner and outer grinding-shells—viz., the temper-screw and the adjusting-bolts—is objectionable, because of the danger of inequality of adjustment of the bolts or the danger of their working loose.

The present invention has for its object to overcome the objections above noted and to 75 provide a simple, cheap, durable, and effective construction of mill that can be readily set up and managed by the unskilled labor commonly used in the operation of this class of mills.

In carrying out my invention I sustain the grinding-rings from the top of the mill, and the several rings are so sustained from such point as to allow each pair of rings to adjust themselves independently of the others. 85 Moreover, the point of connection or suspension of the rings at the top of the mill is more or less loose, so that the rings can have a slight lateral swing or movement in order to compensate for any eccentricity in their shapes 90 and consequent irregularity in movement.

In the accompanying drawings I have shown my invention as applied in two forms of duplex mills, in one of which the innermost and outermost grinders are revolute, 95 while the intermediate grinding-rings and supporting-shell are stationary, and in the other form the innermost and outermost grinders are stationary and the intermediate grinders and their sustaining-shell are revolute. 100 In both forms of my invention, however, it will be seen that the grinding-rings located

about the base of the mill being sustained with respect to each other from the top of the mill, and consequently at a distance from their operative surfaces, there is more or less lateral 5 swing or movement allowed to the grinders to compensate for inequalities of surface or eccentricity in the shape of the rings.

Referring to the accompanying drawings, Figure 1 is a view in central vertical section through a grinding-mill embodying my invention. Fig. 2 is a plan view of the mill with the hopper removed. Fig. 3 is a detail view showing the center-post or cone-post of the mill. Fig. 4 is a view similar to Fig. 1, 15 but illustrating a modified embodiment of the invention. Fig. 5 is a plan view of the construction shown in Fig. 4.

A designates the inner shell or cone of the mill, the base portion of which has its periphery provided with grinding teeth or ribs *a* of usual or suitable construction and arrangement. The upper portion of the cone A is provided with crushing-teeth *b* in suitable number and arrangement, these teeth being 20 adapted to coöperate with corresponding teeth *c*, that depend from the arms C, that are preferably formed integral with and extend inwardly from the intermediate shell C' of the mill. The intermediate shell C' is of conoidal 25 shape, and the interior of its base is furnished with a grinding-ring C² and with teeth C³, that coöperate with the grinding-teeth *a*, formed upon the outer surface of the base of the inner shell A. At the bottom of the 30 intermediate shell C are formed lugs D, that will be bolted to the top of the receiving-box or other convenient support in any suitable manner. From the center of the inner cone or shell A rises the cone-post A', the 35 lower portion of which is preferably of conical contour, as shown in Fig. 3, and this cone-post A' passes upward through a corresponding conical or circular opening in the hub C⁴, that connects the arms C, that project 40 from the body of the intermediate shell C'. Around the intermediate shell C' extends an outer shell E, the interior surface of the base of which is provided with a grinding-ring *e*, that coöperates with the grinding ring or teeth 45 C⁴, formed upon the exterior of the lower part of the intermediate shell C'. From the upper part of the outer shell E extend inwardly the arms E', that are united to a hub E², that is formed with a polygonal opening to receive 50 the corresponding polygonal upper portion of the cone-post A'. The arms E' are cob-crushing arms and coöperate in the usual manner with the arms C beneath them. From the top of the shell E rises a hopper E⁴, into which the 55 ears of corn or like grain to be ground will be delivered. Revolution will be imparted to the outermost shell E by suitable sweeps (not shown) that will be attached to the lugs or 60 studs E⁵, projecting laterally from the upper part of the outer shell E, and inasmuch as the outer shell E is connected with the cone-post 65

A' by the hub E² it is manifest that rotation will be imparted from the shell E to the cone-post A', and consequently to the inner shell or cone A. The cone-post A' is a hollow post, and through it passes an adjusting-screw F, the lower threaded end of this screw passing through a threaded opening in a plate G, that sustains the inner cone A, and the screw F passes also through a plate H, that rests upon the hub E², the screw F being provided with a shoulder or offset *f*, that bears upon the top of the plate H. It will thus be seen that the screw F (the upper end of which is furnished with a suitable hand-wheel f') serves not only to 70 sustain the inner cone or shell A, but also by means of this screw the adjustment of both the inner and outermost shells and grinders with respect to the intermediate shell and its grinder can be effected. The intermediate 75 shell C' is formed with a series of openings c⁵, through which grain will pass outwardly to the outer set of grinders—that is to say, between the lower portions of the intermediate shell C' and the lower portion of the outer 80 shell E.

From the foregoing description it will be seen that when grain is placed within the hopper E⁴ and rotation is imparted (by the sweeps that will be attached to the lugs E⁵) to 85 the outer shell E corresponding rotation will be imparted to the inner shell A, the intermediate shell C' and the grinders at the base thereof remaining stationary. The grain will pass downward between the arms E' and C, 90 thence between the teeth *c* and *b*, and finally a portion of the grain will pass outward between the grinding-rings *a* and C², while a portion of the grain will pass through the opening c⁵ and thence downward between the 95 grinders *e* and C⁴. The proper adjustment of the inner and outer shells A and E with respect to the intermediate shell C' can be readily effected by means of the screw F, and inasmuch as the grinders at the base of the 100 shells are sustained from the bearings at the tops of the shells the grinders will adjust themselves, and thus compensate for any imperfection in the castings, which in this cheap class of mills are seldom or never accurately 105 round or of even thickness. This adjustment of the inner and outer grinding-shells at one operation and by a single screw is a feature of material advantage, and by sustaining the inner and outer shells at their 110 tops and at a distance from the grinding-rings, so that a measure of movement is permitted to allow the grinders to adjust themselves to irregularities, the danger of breakage of parts is avoided, while at the same time the lateral 115 movement or swing of the grinding-rings insures an even grinding of the grain, notwithstanding such irregularities or imperfections in construction.

In duplex mills in which bolts are employed around the bottom for sustaining and adjusting the outermost grinding-ring it is 120

manifest that any irregularity in the adjustment of the several bolts would destroy the proper operation of the mill, whereas when a single temper-screw is employed, as in my present construction, all danger of inequality of adjustment is avoided, since the screw effects the entire adjustment of the grinders, and the lateral play or swing of the grinders from the top support compensates for irregularities or defects of construction.

While in the preferred embodiment of the invention the innermost and outermost shells of the mill are revoluble while the intermediate shell is stationary, still it is obvious that the broader features of my invention may be practiced in a mill in which the intermediate shell is revoluble and the innermost and outermost shells are stationary. Thus by reference to Figs. 4 and 5 it will be observed that the innermost shell A is provided at its lower edge with laterally-extending lugs a^{10} , by which it will be bolted to the box or casing that receives the material passing from the mill. The cone-post or center post A' passes up through the hub of the intermediate shell C', being conical at such point, while the upper polygonal portion of the cone-post enters the hub E² of the outermost shell E. Consequently the innermost and outermost shells remain stationary. The bottom of the intermediate shell E is provided with laterally-extended arms e^8 and e^9 , to one of which will be bolted the main shaft of a sweep E⁵ and to the other of which will be bolted a stay-rod E⁶, leading from the outer end of the sweep. Except in the particulars above noted the construction of the mill last described will be the same as that illustrated upon Sheet 1 of the drawings. It will be seen that the intermediate shell E will be revolved by means of the sweep and the innermost and outermost shells will remain stationary; but the grinding-rings around the base of the mill being sustained from the top-post, so that a measure of lateral play or movement is allowed, it is manifest that the rings will adjust themselves to compensate for irregularities of construction, and thus insure evenness and uniformity in the grinding operation.

It is manifest that the details of construction above set out may be varied without departing from the spirit of the invention, the leading features of which are, first, the supporting of the grinding-rings from the top of the mill by loose connections, so that a measure of lateral play of movement is allowed to the rings, and, second, the use of a single adjusting-screw, whereby the adjustment of the grinders is effected.

Having thus described my invention, what I claim as new, and desire to secure by Letters Patent, is—

1. A grinding-mill of the character described comprising an inner cone provided with a grinding-ring at its base and provided

at its top with a central post or support, an outer shell provided at its base with a grinding-ring and mounted upon said post or support in manner permitting a lateral swing to the grinding-ring of said shell and an intermediate cone-shell provided at its base with inner and outer grinding-surfaces and provided at its top with a hub encircling said cone post or support in manner permitting a lateral swing of the grinding-surfaces of said cone-shell whereby any eccentricity in the shapes of or any irregularity in the movement of the grinding-rings is compensated for.

2. A grinding-mill of the character described comprising an inner cone provided with a grinding-ring at its base and provided at its top with a hollow central post or support, an outer shell mounted upon said post in manner permitting said shell to swing laterally and provided at its base with a grinding-ring, an intermediate cone-shell provided at its base with inner and outer grinding-surfaces coöperating respectively with the grinding-surfaces of the bottoms of the inner cone and outer shell and provided at its top with a hub loosely encircling said post or support and a temper-screw passing through said post or support, whereby the adjustment of the grinders at the base of the mill is effected.

3. A grinding-mill of the character described comprising an inner revoluble cone provided with a grinding-ring at its base and provided at its top with a central post or support, an outer shell connected at its top with said cone post or support of the inner shell and revoluble therewith, and an intermediate stationary cone-shell provided at its top with a hub loosely encircling said cone-post and provided at its base with inner and outer grinding-surfaces coöperating respectively with the grinding-surfaces at the bottoms of the inner cone of the outer shell.

4. In a grinding-mill of the character described, the combination of an inner grinding-cone provided at its base with a grinding-surface and having its upper part provided with teeth, of an outer shell free at its bottom whereby it may swing laterally and connected at its top to the inner shell so as to revolve therewith and provided at its base with a grinding-surface, and an intermediate stationary cone-shell located between the inner and outer shells, said stationary cone-shell having its upper portion provided with teeth to coöperate with the teeth upon the upper portion of the inner cone and being provided at its bottom with inner and outer grinding-surfaces to coöperate with the corresponding grinding-surfaces at the bottoms of the inner cone and outer shell.

5. A grinding-mill of the character described comprising an inner cone provided with a central post or support, an outer shell connected to said post or support of the inner cone and adapted to revolve therewith,

an intermediate grinding cone-shell provided with a hub through which the post of the inner cone projects, said inner cone, said outer shell and said intermediate cone-shell being provided at their bottoms with grinding-surfaces, and an adjusting-screw passing through said central cone-post and provided with

plates and bearings to engage the inner cone and outer shell whereby said parts may be simultaneously adjusted.
